UNITED STATES PATENT OFFICE.

ANSON O. KITTREDGE, OF SLATE HILL, NEW YORK, ASSIGNOR TO JACOB S. THORN, OF PHILADELPHIA, PENNSYLVANIA.

METALLIC ROOFING PLATE OR SHINGLE.

SPECIFICATION forming part of Letters Patent No. 390,236, dated October 2, 1888.

Application filed October 20, 1887. Serial No. 252,873. (No model.)

To all whom it may concern:

Be it known that I, ANSON O. KITTREDGE, of Slate Hill, Orange county, State of New York, have invented a new and useful Improvement in Metallic Roofing Plates or Shingles, of which the following is a true and exact description, reference being had to the drawings, which accompany and form part of this specification.

10 My invention relates to that kind of roofing material now generally known as "metallic shingles" or "tiles," and which is made by bending or stamping the edges of small sheets of metal (generally tin) into such forms that they will register and interlock together, forming tight seams between adjoining plates, which seams alone, or together with an ornamental design stamped up in the visible part of the plate, give to a roof the appearance of one covered 15 with tiles. In covering roofs with this kind of plating, trouble has been met with in securing the shingles to the edges of the roof in such a way as to at the same time secure the plates in place and prevent leakage, and where 20 a section of roof abutted against a higher wall, or two sections met, forming a "valley," it has been usual to employ separate sheets of tin to re-enforce such points.

25 The object of my invention is to furnish special shingles adapted for use at the valleys, eaves, and angles of a roof; and it consists in providing the shingles with plain flat uncorrugated and unseamed flanges extending out from their bottom or side edges and in the 30 plane of the bottom or unembossed portion of the bent or stamped plate beyond the limits of the shingle proper, so that said plain flanges can be bent up or down, either to pass around the edge of the roof at its side or bottom, or 35 to fit into or over a valley or ridge in the roof and form what is called a "flushing-plate."

40 Reference being now had to the drawings, which illustrate my invention, Figure 1 is a plan view of a metal plate having the impress 45 of three diamond-shaped tiles struck up on its surface, with grooves to facilitate its engagement with similar plates, and a plain flange along its lower edge in the plane of its bottom or unembossed surface. Fig. 2 is an edge view 50 of the same plate secured on a roof and with its flange bent around and secured to the eaves. Fig. 3 is a plan view of a plate having a tile

of similar form embossed on it and with its side prolonged to form a flat lapping-flange. Fig. 4 is an edge view of this tile or plate on a roof, showing its flange projecting over the side thereof, ready to be bent around and secured to the edge, as is shown in Fig. 2; and Fig. 5 is a plan view of a tile of somewhat different pattern, and having both its bottom and one edge provided with folding flanges. Such a plate is to be used at a corner.

A is my improved plate.

B is the embossed or seamed part of the plate forming the shingle proper as now generally made.

C are the plain bending flanges, which I form from the same plate as the shingle B, and cause to extend out beyond it in the plane of its bottom or unembossed portions.

D represents the roof to which the plates or shingles are secured.

The adaptability of my invention to all edges and angles of a roof will be at once appreciated, and the advantage of having the flexible flanges to serve as flushing strips and clamps is apparent. The device can be used with nearly if not quite all of the numerous embossed metallic shingles in use.

It is of course not new with me to form a flat edge on the outside of an embossed shingle, as such edges are always provided to serve as nailing-flanges; but my improved shingle has, in addition to such nailing flanges, broad flat extensions, which serve the purposes of flushing strips or clamps, taking the place of the separate metal strips heretofore used for such purposes, and rendering the roofs both more sightly and more secure at exposed angles than the old devices.

Having now described my invention, what I claim as new, and desire to secure by Letters Patent, is—

As a new article of manufacture, an embossed metallic roofing plate or shingle having, in addition to the ordinary nailing-flanges, one or more broad flat plates formed integral with it and extending out from the shingle proper in the plane of its base or unembossed portion, so as to serve as flushing plates or clamps.

ANSON O. KITTREDGE.
